CLAIM

The ornamental design for an intra-cardiac procedure device, as shown and described.

DESCRIPTION

FIG. 1 is a perspective view of an elongate member of an intra-cardiac procedure device;

FIG. 2 is a top view of the elongate member of FIG. 1; FIG. 3 is a bottom view of the elongate member of FIG. 1; FIG. 4 is a left side view of the elongate member of FIG. 1; FIG. 5 is a right side view of the elongate member of FIG. 1;

FIG. 6 is a front view of the elongate member of FIG. 1; FIG. 7 is a back view of the elongate member of FIG. 1; FIG. 8 is another perspective view of the elongate member of FIG. 1, shown in relation to certain additional environmental features;

FIG. 9 is a top view of the elongate member of FIG. 8; FIG. 10 is a bottom view of the elongate member of FIG. 8; FIG. 11 is a left side view of the elongate member of FIG. 8;

FIG. 12 is a right side view of the elongate member of FIG. 8; FIG. 13 is a front view of the elongate member of FIG. 8; and,

FIG. 14 is a back view of the elongate member of FIG. 8. The broken lines showing on the outer surface of the elongate member illustrate the bounds of the claim. The broken lines showing the shaft and other elongate members illustrate the environmental structures. The broken lines form no part of the claimed design.
